COMBINED IMPULSE AND REACTION TURBINE.

No. 813,169.

Specification of Letters Patent.

Patented Feb. 20, 1906.

Application filed December 7, 1905. Serial No. 290,792.

To all whom it may concern:

Be it known that I, CARL PFENNINGER, engineer, a citizen of the Republic of Switzerland, and a resident of Ohmstrasse 1, Munich, in the Kingdom of Bavaria, Germany, have invented certain new and useful Improvements in a Combined Impulse and Reaction Turbine; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to improvements in combined impulse and reaction turbines, the object being to overcome the difficulties presented in the construction of the multiple-stage turbine-drum on which the blades of the reaction-turbine are fixed.

According to this invention it is proposed to construct the drum or portion of the shaft carrying the various blades in a combined impulse and reaction turbine of uniform diameter, or nearly so, over the entire length occupied by the blades and labyrinth packing-flanges. The actuating fluid—steam, for example—flows in one direction through the impulse-turbine and part of the reaction-turbine and then in the opposite direction through the other part of the reaction-turbine, the steam thus traversing the two portions of the reaction-turbine in opposite directions. The subdivision of the reaction-turbine is calculated in such a manner that the two opposed end pressures resulting therein counterbalance each other, and the shaft of the turbine is therefore freed from end thrusts. The impulse-blades are continued until that portion of the turbine is reached at which the full effect of the actuating fluid on the blades is obtained, at which point the reaction-blades commence. Labyrinth packing-flanges are provided at all necessary points on the drum and shaft.

In the accompanying drawing, which illustrates partly diagrammatically one embodiment of the invention, *a* indicates the steam-

admission port; *b*, the impulse-blades; *c'*, that part of the reaction-turbine traversed by the steam in the same direction as the impulse-blades; *c''*, that part of the reaction-turbine which is traversed by the steam in the opposite direction.

d' and *d''* are labyrinth packing-flanges.

e is the exhaust, *f* the stuffing-boxes, through which the shaft passes from the inside of the casing, and *g* the bearings in which the shaft is mounted.

By means of the arrangement described it is possible to have a smooth drum for all the blades in common and of equal, or nearly equal, diameter throughout, which drum may be easily produced from a tube of suitable material, such as wrought-iron or the like.

Having thus described my invention, what I claim as new, and desire to secure by Letters Patent of the United States of America, is—

1. In an impulse and reaction turbine, the combination of a drum of approximately equal diameter throughout its length, a stepped casing in which said drum rotates, a series of impulse-blades carried by said drum and casing, a series of reaction-blades also carried by said drum and casing and forming a continuation of the impulse-blades and a further series of reaction-blades oppositely arranged to the first series.

2. In an impulse and reaction turbine, the combination of a drum of approximately equal diameter throughout its length, a stepped casing in which said drum rotates, a series of impulse and reaction blades carried by said drum and casing, and a further series of reaction-blades at the opposite end of the drum and casing connected to the first series by a passage, whereby the steam is caused to first travel through the impulse-blades then through the first set of reaction-blades and thence backward through the passage to the second set of reaction-blades.

3. In an impulse and reaction turbine the combination of a drum of approximately equal diameter throughout its length, a casing comprising separate chambers, impulse and reaction blades carried by one chamber

and impulse-blades only by the other chamber, the two sets of impulse-blades being connected by a passage capable of reversing the direction of travel of the fluid and packings
5 formed of labyrinth flanges between the drum and casing at the points where the passage of fluid is to be checked.

In testimony that I claim the foregoing as my invention I have signed my name in presence of two subscribing witnesses.

C. PFENNINGER.
